CLAIM

The ornamental design for a housing for a fluid image clock, as shown and described.

DESCRIPTION

FIG. 1 is a perspective view of a housing for a fluid image clock showing my new design;

FIG. 2 is a side elevational view thereof;

FIG. 3 is a top plan view thereof;

FIG. 4 is a front elevational view thereof;

FIG. 5 is a bottom plan view thereof;

FIG. 6 is an elevational view of the side opposite to FIG. 4; and

FIG. 7 is a rear elevational view thereof; and,

FIG. 8 is a perspective view corresponding to housing for fluid image clock with the clock face, liquid and dolphin shown for illustrative purposes only and forming no part of the claimed design.
